No. 866,192.

PATENTED SEPT. 17, 1907.

L. J. CASTIAU.
SPRING WHEEL.
APPLICATION FILED NOV. 12, 1906.

UNITED STATES PATENT OFFICE.

LEOPOLD J. CASTIAU, OF STRATHCONA, ALBERTA, CANADA, ASSIGNOR OF ONE-TENTH TO
CHARLES F. HOVER, OF CONRAD, MONTANA.

SPRING-WHEEL.

No. 866,192.

Specification of Letters Patent.

Patented Sept. 17, 1907.

Application filed November 12, 1906. Serial No. 343,061.

To all whom it may concern:

Be it known that I, LEOPOLD J. CASTIAU, a subject of the King of England, residing at Strathcona, Alberta, Canada, have invented certain new and useful Improvements in Spring-Wheels, of which the following is a specification.

This invention appertains to vehicle wheels of the type containing yieldable spring spokes so as to neutralize and absorb vibration and shock in a manner similar to wheels equipped with pneumatic and cushion tires.

For a full description of the invention and the merits thereof and also to acquire a knowledge of the details of construction of the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a side view of a portion of a vehicle wheel embodying the invention. Fig. 2 is a transverse section of the wheel on the line z—z of Fig. 1. Fig. 3 is a sectional view of a spoke showing the parts on a larger scale.

Corresponding and like parts are referred to in the following description and indicated in all the views of the drawings by the same reference characters.

The vehicle wheel comprises a hub, a rim, and spring spokes, the latter being connected at their ends to the hub and rim in any determined way. The hub comprises spaced members between which the inner ends of the spokes are received and bolted or otherwise secured. The rim or felly 2 may be of any construction according to the design and purpose for which the wheel is constructed and has the outer ends of the spokes firmly attached thereto. As shown, sockets 3 are provided at intervals in the length of the rim and are bolted or otherwise fixed thereto, said sockets receiving the outer ends of the spokes which are pinned, bolted, or made fast thereto, in any accustomed way. The spokes are of like formation, each consisting of sections 4 and 5, a turn-buckle 6, cylinder 7, and a yielding connection between said cylinder and the adjacent section 4. The section 5 is fastened at one end to the socket 3 and its opposite end is threaded. The section 4 makes screw-threaded connection with the turn-buckle 6 and is slidable within an end of the cylinder 7 and is provided with a follower or piston 8 which is arranged within the cylinder and secured to the inner end of the section 4. The opposing ends of the sections 4 and 5 are oppositely threaded; that is, the one is formed with a right-hand thread and the other with a left-hand

thread; hence, upon turning the buckle or coupler 6, which is threaded upon said sections, the latter are either separated or drawn together, according to the direction of rotation of the turn-buckle 6.

The cylinder 7 is of sectional formation and comprises complementary parts, the one fitting within the other and making screw-thread connection therewith, thereby admitting of the cylinder being lengthened or shortened as may be required. The outer section 9 of the cylinder is internally threaded, and its closed end is provided with a polygonal portion 10 to admit of a wrench or other implement being fitted thereto either for turning the section to vary the length of the cylinder or to hold said section against turning when rotating the turn-buckle 6. An angular opening is formed in the closed end of the section 9 to receive an end portion 70 of the section 4 which is of corresponding shape in cross-section. The section 11 is externally threaded to match the threads within the section 9 and its end is tapered to admit of the inner ends of the spokes snugly fitting when grouped about the hub. The follower or piston 8 is slipped upon the end portion of the section 4 operating in the cylinder 7 and is pinned or bolted to said section so as to move therewith. A spring 12 is mounted upon the section 4 and is arranged between the piston 8 and the outer end of the cylinder 7. A 80 similar spring 13 is located upon the opposite side of the piston and between it and the inner end of the cylinder. The spring 13 sustains the inward thrust upon the spoke whereas the spring 12 sustains the outward thrust coming upon said spoke. It is to be understood that the 85 springs 12 and 13 may be replaced by rubber buffers or other yielding means commonly employed to admit of a rebounding action.

It is to be understood that each of the spokes sustains a proportionate amount of the load and strain either by 90 a compressive or a pulling action, according to the position of the spoke in the rotation of the wheel. By this means the load is equalized upon the wheel and the latter need not be of excessively heavy structure in its parts. It will also be observed that the hub and rim of 95 the wheel are adapted to yield relatively, the springs serving to compensate for shock and vibration, rendering the vehicle equipped with such wheels comparatively easy riding.

Having thus described the invention, what is claimed is:

1. In a wheel, the combination of a spoke comprising adjustable sections, an adjustable cylinder slidably mounted upon one of said adjustable sections, and yielding means between a member of said adjustable cylinder and 105 a member of the adjustable sections.

2. In a wheel of the character specified, the combination of sections, means for relatively adjusting said sections, a cylinder slidable upon one of said sections and

adapted to turn therewith, said cylinder comprising complementary parts having screw-thread connection to admit of lengthening or shortening the cylinder, a piston fast upon the inner end of the section extended into the cylinder, and yielding means arranged upon opposite sides of the piston and between it and the outer ends of the respective parts of the cylinder.

3. In a wheel of the character specified, the combination of spoke sections having their opposing ends oppositely threaded, a turn-buckle mounted upon the threaded ends of said sections, a cylinder mounted upon one of said spoke sections to slide thereon and to turn therewith, said cylinder comprising complementary parts having

screw-thread connection to admit of lengthening or shortening said cylinder, a piston fast to the end of the spoke section extended within the cylinder, and springs arranged upon opposite sides of the piston and concealed within the cylinder and exerting an outward pressure against outer ends of the respective cylinder sections. 15

In testimony whereof I affix my signature in presence of two witnesses. 20

LEOPOLD J. CASTIAU. [U. S.]
